(57) **CLAIM**

The ornamental design for a pet bowl, as shown and described.

DESCRIPTION

FIG. 1 is a front elevational view of a pet bowl showing our new design;

FIG. 2 is a rear elevational view thereof;

FIG. 3 is a right side elevational view thereof, the left side elevational view being a mirror image thereof;

FIG. 4 is a top plan view thereof;

FIG. 5 is a first perspective view thereof; and,

FIG. 6 is a second perspective plan view thereof.

The broken lines shown in the drawings illustrate portions of the pet bowl that form no part of the claimed design.
